UNITED STATES PATENT OFFICE.

WILHELM F. JAENECKE, OF SALAMANCA, NEW YORK.

CLUTCH.

SPECIFICATION forming part of Letters Patent No. 728,720, dated May 19, 1903.

Application filed March 12, 1902. Serial No. 97,906. (No model.)

To all whom it may concern:

Be it known that I, WILHELM F. JAENECKE, a citizen of the United States, residing at Salamanca, in the county of Cattaraugus and State 5 of New York, have invented a new and useful Clutch, of which the following is a specification.

The present invention relates to clutches, and while particularly intended as an improvement in clutch-pulleys it will be evident that it may be employed in other connections.

One of the objects of the invention is to provide a clutch which is positive in its operation and will not be liable to accidentally lock when in inoperative position or unlock when in operative position.

A further object is to provide a clutch in which the mechanism is completely inclosed, 20 so as to be protected from injury, and having no projecting portions liable to catch the clothing of workmen employed about the same, thereby practically eliminating danger of accidents from this cause.

An embodiment of the invention, which has proven entirely satisfactory, is illustrated in the accompanying drawings, as described in the following specification; but changes 30 may be made from this embodiment, provided they are within the scope of the claims hereto appended.

In the drawings, Figure 1 is a face view of the pulley. Fig. 2 is a vertical longitudinal sectional view of the same, taken on the line 35 X X of Fig. 1. Fig. 3 is a vertical transverse section taken on the line Y Y of Fig. 2. Fig. 4 is a detail sectional view through the fixed clutch member, clearly illustrating the manner of mounting the operating-shaft. Fig. 40 5 is a view in elevation of the sprocket-wheel and operating-shaft, and Fig. 6 is a vertical sectional view through the adjusting-screw.

Similar reference-numerals designate corresponding parts in all the figures of the drawings.

The clutch as illustrated consists of three elements or members, a loose member 10, a fixed member 11, and a throw-off head 12, these several members being preferably located upon a single shaft, as 13. It will be understood that the terms "loose" and "fixed" as applied to the clutch members

are merely relative to distinguish between them for the sake of clearness and to avoid any danger of confusion in the description 55 and claims.

The loose member 10 in the present instance is in the form of a pulley comprising a hub 14, a web 15, and a rim 16, the hub being provided with a bushing 17 and being 60 loosely journaled upon the shaft 13. A stop-collar 18, fastened to the shaft by means of a set-screw 19, prevents longitudinal movement of the loose member in one direction. Located upon the inner face of the rim 16, adjacent to the web 15, is a bearing-flange 20, having an annular V-shaped channel or groove 21, the purpose of which will hereinafter more fully appear.

The fixed member 11 comprises a hub 22, 70 secured to the shaft 13 by means of a key 23, said key being held against accidental displacement by a set-screw 24. This hub is provided with a flange or cap-plate 25, that fits within the rim 16 of the loose member directly adjacent to the bearing-flange 20. Pivoted upon the inner face of the cap-plate 25 are jaws 26, carrying friction-blocks 27, that are located in the annular groove 21 and are movable into and out of engagement with the 80 surface thereof upon the movement of the jaws. These jaws are each pivoted at one end upon a pin 28, screwed into or otherwise attached to the cap-plate 25. Their opposite ends are connected by a screw 29, the opposite ends of which are right and left threaded, and are screwed into similarly-threaded nuts 30, arranged in sockets made for the purpose in the ends of the jaws, said nuts being held in place by set-screws 31. This screw 29 is 90 provided with a sprocket-wheel 32, rigidly fixed thereto.

On the outer side of the cap-plate 25 is arranged an operating-shaft 33, which is journaled in spaced ears 34 and is provided with 95 a crank-arm 35 and a sprocket-wheel 36. This sprocket-wheel is revolvably adjustable upon the operating-shaft, and to this end the portion of said shaft which fits between the ears 34 is angular in cross-section, while the 100 sprocket-wheel is provided with a similarly-shaped opening that receives this portion of the shaft. In order that the operating-shaft may be removed, one of the ears 34 has an

enlarged opening through which the angular portion of the shaft will pass, said opening being normally closed by a bushing 37. The sprocket-wheel 36 is preferably larger than the sprocket-wheel 32 of the screw, and the two are connected by a chain, as 38, so that upon the rotation of the operating-shaft 33 the screw will also be rotated and to a greater degree.

10 The throw-off head 12 is slidably mounted upon the shaft 13 and the fixed member 11 and is movable toward and from the cap-plate 25. This throw-off head is provided with a suitable annular groove 39, adapted 15 to receive the usual operating-lever. It furthermore has a casing portion 40, that incloses the operating-shaft and the other mechanism located on the fixed member outside the cap-plate. As a result the entire mechanism is completely inclosed. This throw-off head is connected with the operating-shaft 33 in the following manner: A hollow adjusting-screw 41 is threaded into the casing portion 40 and is counterbored to provide an 20 annular shoulder 42. A head 43 is swiveled in the adjusting-screw by having a stem 44 located in the bore thereof and having an upset portion 45, that engages over the shoulder 42. A link 46 pivotally connects this 25 head with the end of the crank-arm. It will therefore be seen that when the throw-off head is moved in one direction through the connection above described the operating-shaft will be rotated, consequently rotating 30 the screw 29, which will force the jaws apart and into engagement with the loose member. As a result the two members will be locked together and the loose member will rotate with the shaft. On the other hand, when the 35 throw-off head is moved in the opposite direction a reverse movement of the several elements will take place, so that the jaws will be moved toward each other, thereby disengaging the loose member. Should the bearing-blocks 27 of these jaws become worn, the 40 wear may be taken up by rotating the adjusting-screw 41, and if this is not sufficient the operating-shaft 33 may be withdrawn from the sprocket-wheel 36 and rotated so as to 45 throw the crank-arm into a different position with relation thereto, and the screw 41 may be then adjusted to get the exact movement required.

The advantages for this construction may 50 be summed up as follows: In the first place the operating mechanism is entirely inclosed by the cap-plate and the throw-off head, so that it is protected from injury and there are no projecting portions to catch the clothing 55 of workmen. Further than this the specific construction set forth insures a positive locking and unlocking movement and is not liable to be accidentally operated by the vibrations of the shafting or machinery. Further than 60 this means are provided for taking up the wear of the jaws upon the loose member, so

that the necessity of frequent renewals of these elements are not necessary.

From the foregoing it is thought that the construction, operation, and many advantages of the herein-described invention will be apparent to those skilled in the art without further description, and it will be understood that various changes in the size, shape, proportion, and minor details of construction 75 may be resorted to without departing from the spirit or sacrificing any of the advantages of the invention.

Having thus described my invention, what I claim as new, and desire to secure by Letters 80 Patent, is—

1. The combination with a loose clutch member having a projecting rim, of a fixed member having a cap-plate that fits within the rim of the loose member, and has its inner 85 face spaced therefrom forming a chamber, a jaw mounted upon the inner face of the cap-plate of the fixed member, and arranged in the said chamber, said jaw being movable into and out of engagement with the loose member, operating means for moving the jaw, said means being located upon the fixed member exterior to the cap-plate and passing entirely through the same, a throw-off head 90 movably mounted with relation to the fixed member and having a positive connection with the operating means, said head having a casing portion that incloses said operating means.

2. The combination with a loose clutch member, of a fixed member, a jaw carried by the fixed member and movable into and out of engagement with the loose member, operating means for the jaw also carried by the fixed member, a throw-off head movably mounted 105 with relation to the fixed member and having an adjustable connection with the operating means, said head having a casing portion that incloses said operating means.

3. The combination with a loose clutch member, of a fixed clutch member, a jaw carried by the fixed member and movable into and out of engagement with the loose member, a screw having a connection with the jaw and provided with a sprocket-wheel, another 115 sprocket-wheel journaled upon the fixed member, a chain connecting the two wheels, a throw-off head movably mounted with relation to the fixed member, and a connection between the throw-off head and the latter 120 sprocket-wheel to rotate the same upon the movement of the head.

4. The combination with a loose clutch member, of a fixed clutch member, a jaw carried by the fixed member and movable into and 125 out of engagement with the loose member, a screw having an engagement with the jaw and provided with a sprocket-wheel; a shaft journaled upon the fixed member and carrying a sprocket-wheel and a crank-arm, a chain 130 connecting the two sprocket-wheels, a throw-off head movably mounted with relation to

the fixed member, and a connection between the throw-off head and the crank-arm of the shaft.

5. The combination with a loose clutch member, of a fixed clutch member, a jaw carried by the fixed member and movable into and out of engagement with the jaw and provided with a sprocket-wheel, a shaft journaled upon the fixed member and carrying a sprocket-wheel and a crank-arm, said sprocket-wheel having a revoluble adjustment upon the shaft, a chain connecting the two sprocket-wheels, a throw-off head movably mounted with relation to the fixed member, and a connection between the throw-off head and the crank-arm of the shaft.

6. The combination with a loose clutch member, of a fixed clutch member, a jaw carried by the fixed member and movable into and out of engagement with the loose member, a screw having an engagement with the jaw and provided with a sprocket-wheel, a shaft journaled upon the fixed member and carrying a crank-arm, the said shaft having a portion angular in cross-section, a sprocket-wheel detachably fitted upon the angular portion of the shaft, a chain connecting the two sprocket-wheels, a throw-off head movably mounted with relation to the fixed member, and a connection between the throw-off head and the crank-arm of the shaft.

7. The combination with a loose clutch member, of a fixed clutch member, a jaw carried by the fixed member and movable into and out of engagement with the loose member, a screw having a connection with the jaw and provided with a sprocket-wheel, another sprocket-wheel journaled upon the fixed member, a chain connecting the two sprocket-wheels, a throw-off head movably mounted with relation to the fixed member, and an adjustable connection between the throw-off head and the latter sprocket-wheel to rotate the same upon the movement of the head.

45 8. The combination with a loose clutch member, of a fixed clutch member, a jaw carried

by the fixed member and movable into and out of engagement with the loose member, operating mechanism for moving the jaw, a throw-off head movable with relation to the fixed member, and an extensible connection between the throw-off head and the operating mechanism.

9. The combination with a loose clutch member, of a fixed clutch member, a jaw carried by the fixed member and movable into and out of engagement with the loose member, operating mechanism for moving the jaw, a throw-off head movable with relation to the fixed member, a link connected to the operating mechanism, and an adjusting-screw threaded into the throw-off head and having a swivel connection with the link.

10. The combination with a loose clutch member, of a fixed clutch member, a jaw carried by one member and movable into and out of engagement with the other member, operating mechanism in the form of gearing for moving the jaw, said mechanism being mounted upon the member having said jaw, a throw-off head movable with relation to the members, and an adjustable connection between the throw-off head and the gearing.

11. The combination with a loose clutch member, of a fixed clutch member, a jaw carried by one member and movable into and out of engagement with the other member, means for moving the jaw, said means including an operating-shaft and a gear-wheel having a revoluble adjustment on the operating-shaft, a throw-off head movable with relation to the members, and a connection between the throw-off head and the operating-shaft.

In testimony that I claim the foregoing as my own I have hereto affixed my signature in the presence of two witnesses.
